[57] CLAIM

The ornamental design for a reflective rat trap pedal, as
shown and described.

DESCRIPTION

FIG. 1 is a top perspective view of one end of a reflective rat trap pedal showing my new design.

FIG. 2 is a bottom perspective view of the opposite end thereof.

FIG. 3 is a side elevational view thereof.

FIG. 4 is an elevational view of the left end of FIG. 1.
FIG. 5 is an elevational view of the left end of FIG. 2.
FIG. 6 is a top perspective view of one end of a reflective rat trap pedal showing a second embodiment of my new design.

FIG. 7 is a bottom perspective view of the opposite end of the embodiment shown in FIG. 6.

FIG. 8 is a side elevational view of the embodiment shown in FIG. 6.

FIG. 9 is an elevational view of the left end of the embodiment shown in FIG. 6.

FIG. 10 is an elevational view of the left end of the embodiment shown in FIG. 7.

FIG. 11 is a top perspective view of one end of a reflective rat trap pedal showing a third embodiment of my new design.

FIG. 12 is a bottom perspective view of the opposite end of the embodiment shown in FIG. 11.

FIG. 13 is a side elevational view of the embodiment of FIG. 11.

FIG. 14 is an elevational view of the left end of the embodiment shown in FIG. 11.

FIG. 15 is an elevational view of the left end of the embodiment shown in FIG. 12.

The side opposite to those shown in FIGS. 3, 8, 13 of the
drawing is substantially a mirror image of the sides
shown therein.
